UNITED STATES PATENT OFFICE.

WALTER R. SCHLAGE, OF SAN FRANCISCO, CALIFORNIA.

INDICATING PUSH-BUTTON.

1,021,339.

Specification of Letters Patent. Patented Mar. 26, 1912.

Application filed August 1, 1911. Serial No. 641,762.

To all whom it may concern:

Be it known that I, WALTER R. SCHLAGE, citizen of the United States, residing in the city and county of San Francisco and State 5 of California, have invented new and useful Improvements in Indicating Push-Buttons, of which the following is a specification.

This invention relates to an indicating 10 push-button.

It is the object of this invention to provide a push-button, which is so constructed and arranged that it may be employed as an indicator, and which is particularly adapted 15 for use in operating electrical bells in offices, residences, and the like, for indicating to the operator whether the inmates are "in" or "out".

A further object is to provide a simple 20 means for setting the device to expose either of the indicating characters "in" and "out" or other marks for denoting whether the person called is present or absent.

Another object is to provide a device of 25 the above character, which is simple in construction and operation and which can be manufactured and installed at small cost.

The invention consists of the parts and the construction and combination of parts 30 as hereinafter more fully described and claimed, having reference to the accompanying drawings, in which—

Figure 1 is a vertical section of the invention partly in elevation. Fig. 2 is a plan 35 view of same. Fig. 3 is an inverted plan view, showing the adjusting device. Fig. 4 is a section on the line X—X of Fig. 1. Fig. 5 is a plan view, showing the push-button as depressed to expose the indicating character 40 "in."

In the drawings, A represents a cylindrical casing formed on an escutcheon plate 2, and which is adapted to be mounted on a door casing 3, or the like. Mounted within 45 the casing A is a cylindrical block 4, of approximately the same diameter as the casing, and which block is preferably formed of wood or other insulating material.

Formed on the block 4 is a push-button 5, 50 which extends through a perforation 6 formed in the outer end of the casing A, and by means of which the block 4 may be moved inwardly in the casing A in opposition to a spiral spring 6 which is disposed in the casing 55 and is tensioned to bear between the block 4 and an insulating plug 7, rigidly

mounted in the open end of the casing A, as shown in Fig. 1; the spring 6 normally retaining the block 4 and push-button in their outermost position.

Mounted in the plug 7, and extending therethrough, are electrical conductors 8, the inner ends of which are bent outwardly and form contact members, which are adapted to be electrically connected by means of a contact plate 9 mounted on the block 4, when the latter is moved into its innermost position, by means of the push-button 5. The block 7 forms an abutment to limit the forward movement of the block 4. The outer ends of the conductors 8 connect with binding posts 10 on the plug 7, to which are attached the terminals of positive and negative electrical conductors 11 and 11' leading from any suitable source of electrical supply and connecting with any desired electrical alarm bell in the usual manner, not necessary to be here shown.

Formed in the upper face of the cylinder A is an elongated slot 12 which extends circumferentially of the casing and is so disposed as to expose a portion of the surface of the block 4 adjacent to its inner end, as shown in Fig. 1. Formed on the concealed portion of the block 4, adjacent the slot 12, 85 are the indicator characters "In" which are designed to be exposed in the slot 12 when the block 4 and push-button 5 are in their innermost position, as shown in Fig. 5, and in which position the contacts 8 are closed 90 to sound the alarm actuated through the conductors 11 and 11'; the word "In" serving to denote that the person called is present. Formed on the block 4 peripheral in alignment with the indicating word "In" 95 is the word "Out" which is disposed to one side of the slot 12 and normally concealed. When it is desired to expose the word "Out" in the slot 12 instead of the word "In" the block 4 is rotated a partial revolution so as 100 to dispose the word "Out" in the position previously occupied by the word "In." This rotation of the block 4 is accomplished by means of a pin 13 in the block 4, which extends through a peculiarly shaped slot 105 formed on the underside of the casing A, as shown in Figs. 3 and 4. The above mentioned slot is formed with a peripherally extending portion 14 which terminates at each end in transverse slots 15—15^a, arranged at 110 right angles to the peripheral slot 14, and which join with the portion 14 intermediate

their ends. The pin 13 travels in the slot 15 when the bottom 5 and block 4 are moved inwardly to expose the word "In" in the slot 12, and travels in the slot 15^a when the 5 block 4 moves forward to expose the word "Out"; the pin 13 being moved back and forth through the peripheral slot 14 between the slots 15—15^a to rotate the block 4 to dispose either the "In" or "Out" characters 10 in position to be exposed in the slot 12.

The block 4 is designed to be set by the person called to indicate to the caller whether he is in or out, this information being imparted to the caller through the slot 12 when 15 the push-button 5 is pressed. It is obvious, however, that the characters "In" and "Out" may be arranged on the periphery of the block 4 so as to register with the slot 12 when the block is in its outermost position 20 so as to constantly expose the characters. In setting the block 4 it is necessary to slightly depress the button 5 to bring the pin 13 into alinement with the slot 14 before the block can be turned; the pin 13 being normally 25 engaged in the outer end of either the slot 15 or 15^a to prevent the block 4 being accidentally turned when the push-button 5 is in its normal outermost position.

While I have shown the invention as applied to a push-button for operating electrical contacts to sound an alarm, it is obvious that other alarm mechanisms may be actuated by the depression of the button, or that the button may be used separate from 35 alarm devices. It is also manifest that other indicating characters than those described may be employed if desired.

Having thus described my invention what I claim and desire to secure by Letters Patent, is—

1. A push button having a combined longitudinal and angular movement, a guide casing in which said push button is reciprocally and turnably mounted, said casing having a 45 slot formed in its side and said push button having characters adapted to be exposed through said slot, and means for adjusting the push button angularly to expose differ-

ent characters in said slot when the push button is moved longitudinally. 50

2. A push-button, an indicator carried by the push-button, a guide casing in which said indicator is reciprocally mounted, a slot formed in said casing, indicating characters formed on the indicator and adapted 55 to be exposed through said slot, and means for adjusting the indicator to expose different characters in said slot, said means consisting of a pin on the indicator extending through a slot formed in the casing. 60

3. A push-button, an indicator carried by the push-button, a guide casing in which said indicator is reciprocally mounted, a slot formed in said casing, indicating characters formed on the indicator and adapted 65 to be exposed through said slot, and means for adjusting the indicator to expose different characters in said slot, said means consisting of a pin on the indicator extending through a slot formed in the casing, said 70 slot arranged to admit of reciprocal movement of the pin lengthwise of the casing and also peripherally thereof.

4. A push-button, an indicator carried by the push-button, a guide casing in which 75 said indicator is reciprocally mounted, a slot formed in said casing, indicating characters formed on the indicator and adapted to be exposed through said slot, means for adjusting the indicator to expose different 80 characters in said slot, said means consisting of a pin on the indicator extending through a slot formed in the casing, said slot arranged to admit of reciprocal movement of the pin lengthwise of the casing and 85 also peripherally thereof, and means operable by said indicator for completing an electrical circuit.

In testimony whereof I have hereunto set my hand in the presence of two sub- 90 scribing witnesses.

WALTER R. SCHLAGE.
